UNITED STATES PATENT OFFICE

KENNETH ALBERT MCCOY, OF FULLERTON, CALIFORNIA, ASSIGNOR OF ONE-HALF TO
ESTEE T. BROWN, OF FULLERTON, CALIFORNIA

SAFETY SWINGING FINGER BOARD FOR WELL DRILLING DERRICKS

Application filed January 2, 1930. Serial No. 418,100.

My invention relates to a safety swinging finger board for well drilling derricks.

Finger boards are used in well drilling derricks extending inwardly from one of the sides and are utilized to guide the drill pipe, well casing or the like when stacking on a derrick floor, for inserting or removal from the well. The finger boards are sometimes struck by the elevator or other of the hoisting equipment and if rigid, these are sometimes broken. An object of my invention is a finger board which may tilt upwardly or downwardly when struck and thereby allow passage of the elevator or other part of the driven equipment without breakage of the finger board.

Another object of my invention is supporting the finger board in part by a resilient brace, which brace is adapted to compress if the finger board is struck in a downward direction and thus allow passage of the drilling equipment without breaking the board, the resilient brace then returning the finger board to its original horizontal position.

Another object of my invention is a finger board mounting which may swing upwardly when struck by equipment being hoisted and allow such equipment to pass and then the finger board will fall on the supporting resilient brace.

Another object of my invention is a swivel mounting for the finger board as a whole, so that this may be shifted from a position for stacking pipes, to a position aligned closely with one side of the derrick and thereby allow full use of the derrick for hoisting and lowering well equipment without danger of striking the finger board.

Another detailed object and feature of my invention is having an extensible finger end which may be moved in and out to extend the effective length of the finger board; this end being attached to a tilting finger board tip and secured in various extended positions.

Another detail feature of my invention is equipping the derrick with a duplicate finger board to operate on opposite sides of the elevator cables so that the drill pipe or casing may be stacked at opposite sides of the derrick and both of these finger boards being

braced by angular braces extending outwardly from a substantial bracket in the center of one side of the derrick; the finger boards being swivelly mounted on a vertical axis to swing both parallel to the same side of the derrick and close to such side.

In constructing my invention I utilize suitable brackets extending inwardly from the side frame of a derrick and in these brackets I have a vertically mounted post, the mounting including ball bearings so that the posts will rotate or swivel readily. The finger board is rigidly secured to the post and extends horizontally therefrom and has a finger tip with a horizontal pivot so that the tip may tilt upwardly or downwardly when struck by well equipment. The tip is provided with a telescopic end piece which may be adjusted inwardly or outwardly and secured by a pin. The finger board is braced in the desired operative position by a diagonal brace connected to one side of the derrick and engaging the finger board and the tiltable finger tip is supported by a resilient brace including a spring and a bar retainer thereby, having a supporting element at the upper end to engage the underside of the finger tip. Thus if the finger tip is thrust downwardly, this brace can be compressed.

My invention is illustrated in connection with the accompanying drawings, in which

Fig. 1 is a perspective view of a derrick showing my finger board equipment installed therein;

Fig. 2 is a horizontal section of the derrick taken above the finger board, as if on the line 2—2 of Fig. 1 in the direction of the arrows;

Fig. 3 is a side elevation of one of the finger board mountings taken in the direction of the arrow 3 of Fig. 2;

Fig. 4 is a plan of the finger board and mounting taken in the direction of the arrow 4 of Fig. 3;

Fig. 5 is a detail section through the resilient brace on the line 5—5 of Fig. 3;

Fig. 6 is a detail end elevation taken in the direction of the arrow 6 of Fig. 3.

In the drawings, the well derrick is indicated by the numeral 11 and at a suitable

elevation has a platform 12 encircling the derrick which is sometimes designated as a run around platform. The derrick in the frame has horizontal connecting beams 13 attached to the corner posts 14.

In my construction I utilize upper and lower brackets 15 and 16 secured to the side of the derrick and these may be secured to the horizontal beams 13. These brackets are illustrated as being formed of flat bar metal with angularly bent ends 17 and circular bent ends 18. Such ends enclose a post 19 and have friction bearings 20. The ball bearings allow free rotation of the finger board designated generally by the numeral 21 and attached to the post 19. The finger board has a solid inner portion 22 welded or otherwise secured to the post 19 and has a finger tip 23 mounted on a horizontal pivot 24. The finger board and the end portion 22 have a tongue and a slot connection. The finger end 25 is mounted to telescope in the finger tip section and has a series of vertical openings 26 therethrough which are engaged by a pin 27 passing through the holes 28 in the upper and lower surface of the finger board tip which is preferably made rectangular and hollow to accommodate the end.

At the side of each of the finger boards and on the section rigid with the post, there is an eye structure 29 which is engaged by a detachable link 30. This link gives a pivoted connection at one end with a bracket 31 on one side of the derrick and such link preferably having a pin connection with the eye structure 29 on the finger board. This arrangement holds the finger board in fixed position when extended inwardly in the derrick. The finger board tip is held in its horizontal position by a resilient brace designated generally by the numeral 32. This brace comprises a relatively large tube 33 secured solidly to the post 19 and having a coupling 34 and a smaller tube 35, such tube having preferably a squared interior as indicated at 36 in Fig. 5 and in this squared section there is a telescopic bar 37. Such bar has a head 38 on the inside which is engaged by a spring 39 mounted in the enlarged tube 33 and bearing respectively on the head and on the post 19 or other fixed structure.

The bar 37 has a large roller wheel 40 mounted on the end and this wheel bears on the side portions of the finger board tip. A suspending rod 41 connects between the fixed part 22 of the finger board and the interiorly squared tube 35. The roller 40 and the bar 37 thus have a resilient mounting; the roller bearing normally on the underside of the finger board tip and allowing depressing of this when necessary. This roller 40 is constructed so that it clears the pin 27 so that the finger board tip may move up and down and the roller roll on the lower

surface of the tip when it is pressed downwardly.

The finger board may be struck on the end to either tilt up into the upper dotted position of Fig. 3, or it may be forced downwardly to occupy the lower dotted position of Fig. 3. When thrust to this down position the bar 37 having the roller 40 is thrust into the squared tube 35 and compresses the spring 39, thus giving a resilient support but still allowing the finger board end to tilt down when struck by the drilling equipment and without damaging the finger board end. When the object striking the finger board end is passed in a downward direction, the bar 37 turns to its normal position. If the finger board is struck into the upper position by upwardly moving well equipment, it immediately drops back onto the roller 40 by the action of gravity.

In connection with my invention I have not illustrated a fourble board or so-called monkey board used in connection with placing drill pipe or casing in the proper stack in a derrick, but it is understood that these may be utilized if desired. The link 30 thus holds the finger board in its correct position, extending inwardly in the derrick and the brace 32 holds the finger tip end in the same horizontal plane as the fixed section 22. If it is desired to swing the finger board into the side dotted position shown in Fig. 2, the link is disconnected and on account of the ball bearing connection the finger board may readily be swung to one side and occupy a position parallel to the side of the derrick from which the finger board is swung.

Various changes may be made in the principles of my invention without departing from the spirit thereof as set forth in the description, drawings and claims.

I claim:

1. In combination with a well derrick, a finger board connected thereto and having a movable portion shiftable in a vertical plane above and below the horizontal position, an under support for the movable portion to hold such portion in a horizontal position, the movable portion being free to move upwardly above the said support, the said support being depressible on downward movement of the movable portion and having means to return the movable portion to its horizontal position.

2. In combination with a well derrick, a finger board having a horizontal portion connected to the derrick and a movable finger tip movable in a vertical plane on a horizontal pivot, a resilient support engaging the under side of the tip and holding said tip in a horizontal position, the said support being depressible on depression of the tip and returning said tip after depression to its normal position.

3. In combination with a well derrick as

- claimed in claim 2, the movable support having a slidable bar and a telescopic fitting to house said bar with a spring in said fitting, the finger tip being movable upwardly above the horizontal and above the said support, the 5 said support reengaging the finger tip on the return downward movement of the tip.
4. In combination with a well derrick, a horizontal finger board connected thereto and 10 having a movable finger tip movable in a vertical plane, a resilient support with means to connect said support to the derrick engaging the under side of the movable finger tip, said support being depressible when the finger 15 tip is depressed, the tip being movable upwardly above the horizontal above the support, and an end portion slidably longitudinally of the finger tip with means to adjust the position of said end.
- 20 5. In combination with a well derrick, a finger board having means to connect same to the derrick to occupy a horizontal plane and having a finger tip mounted on a horizontal pivot to move in a vertical plane, the tip having a slidable end with means to adjust 25 said end in relation to the tip, a base having a tube with means to connect said tube to the derrick, a bar slidably in said tube, a spring in the tube bearing against the bar, means on 30 the end of the bar to engage and support the finger tip, the said bar being depressible on depression of the finger tip below the horizontal, the tip in its movement above the horizontal becoming free of the said bar.
- 35 6. In combination with a well derrick as claimed in claim 5, the said bar having a roller on the end engaging the underside of the finger tip, the said tip and the removable end having a pin and slot connection and a 40 suspending rod connected from the brace to the non-vertically movable part of the finger.
7. In combination with a well derrick, a post having a pivotal mounting from one side of the derrick, a finger board having a portion rigidly connected to the post to swing in 45 a horizontal plane, and means connected to one side of the derrick to retain the finger board extending inwardly in the derrick, the said finger board on release of said means being adapted to occupying a position parallel to the side supporting the post.
8. In combination with a well derrick, a pair of brackets connected to one side, a post 55 pivotally mounted at the top and bottom in said brackets, a finger board having a portion fixed to said post to swing in a horizontal plane, and means to position said finger board at right angles to the side having the brackets thereon, the said finger board being 60 shiftable to a position parallel to the said side.
9. In combination with a well derrick, a pair of brackets secured to one side, a post pivotally mounted in said brackets and having a finger board rigidly connected thereto, 65 a brace for the finger board connected to the post, a positioning means interconnecting one side of the derrick and the finger board to retain said board extending inwardly in the derrick, the said means being releasable and the board being shiftable to a position parallel to the side supporting the brackets. 70
10. In combination with a well derrick as claimed in claim 9, the finger board having a tip pivotally mounted to swing in a vertical plane and the brace having a telescopic 75 mounting to depress on depression of the finger board, and means to return said brace to its original position.
11. In combination with a well derrick, upper and lower brackets connected to one side, 80 a post mounted in said brackets to rotate and having a finger board connected thereto, the said finger board having the finger tip pivotally mounted movable in a vertical plane, a telescopic brace connected to the post and having means engaging the finger tip, the said brace being collapsible on downward pivoting of the finger tip, means in the brace to return the finger tip to its original horizontal position, the said tip being tilttable upwardly above said horizontal position and the brace remaining substantially in its original position, and a link connected to the side of the derrick having the brackets, having a detachable connection with the finger board to 85 retain said finger board in a position at right angles to the supporting side of the derrick, said link being releasable and the finger board movable to a position parallel to the 90 said side of the derrick. 95
12. In combination with a well derrick, upper and lower brackets connected to one side, a post having a rotatable mounting in said brackets and having a finger board rigidly connected thereto, the finger board having a tip pivotally connected thereto to swing in a vertical plane, the said tip having a hollow section with a movable end part telescoping 100 therein and means to adjust the end portion, a brace having a tube and a bar telescoping therein, and bar having means to engage and support the finger tip, a spring in the tube engaging the bar to retain the finger tip in its horizontal position, the said bar depressing the spring on the downward pivoting of the 105 finger tip and a link connected to one side of the derrick and to the finger board to retain such board at right angles to the supporting side of the derrick, the link being removable and the finger board shiftable parallel to said side of the derrick. 110
13. In combination with a well derrick, a pair of posts connected to one side, said posts being vertical, a finger board connected to each post to swing in a horizontal plane 120 and interconnecting means between said finger board and the derrick to retain said boards extending inwardly in the derrick and on opposite sides of the center of the derrick. 125
14. In combination with a well derrick, a pair of posts connected to one side, said posts being vertical, a finger board connected to each post to swing in a horizontal plane and interconnecting means between said finger board and the derrick to retain said boards extending inwardly in the derrick and on opposite sides of the center of the derrick. 130

14. In combination with a well derrick, two pair of brackets connected thereto, a post pivotally mounted in each pair, a finger board connected to each post to swing in a horizontal plane, a pair of links connected to the side of the derrick having brackets thereon and each having a connection to one of the finger boards, the said links retaining the finger boards at right angles to the said side of the derrick and being releasable whereby the finger boards may be shifted parallel to the said side of the derrick.
15. In combination with a well derrick as claimed in claim 14, each of the finger boards having a pivotally mounted tip to swing in a vertical plane and a telescopic resilient brace connected between each post and each finger tip the said brace being compressible on downward pivoting of the finger tip and shiftable to return said tip to its normal horizontal position, the said tip being shiftable upwardly above the said brace and returned to its horizontal position by gravity.
16. In combination with a well derrick, a pivotally mounted vertical post, a finger board connected thereto to swing in a horizontal plane, a finger tip mounted on the board to swing in a vertical plane, a brace fixedly connected to the post and having an engagement with the finger tip, said brace normally holding the tip in a horizontal position but permitting the tip to rise above the said brace, the said brace being compressible on depression of the tip, and having means to return the tip to the horizontal position.
17. In combination with a well derrick, upper and lower brackets extending inwardly from one side of the derrick, a vertical post journaled in said brackets and having a finger board attached thereto, the post and board being rotatable, whereby the board may rotate in a horizontal plane, a finger tip connected to the board to swing in a vertical plane, a brace connected to the post and having a resilient supporting element engaging the tip, said supporting element receding on depression of the tip and returning said tip to a horizontal position, and a link having a pivotal connection to one side of the derrick and detachable from the finger board to permit swinging the finger board to a position normal to the side supporting the brackets to a position parallel to said side.

In testimony whereof I have signed my name to this specification.

KENNETH ALBERT McCOY.
